United States Patent Office

Des. 204,133

Patented Mar. 22, 1966

204,133

DIAPER CLASP

Ling H. Lee, 207 S. Barksdale, Memphis, Tenn.

Filed Aug. 16, 1965, Ser. No. 86,587

Term of patent 14 years

(Cl. D17—3)

FIG. 1

FIG. 2

FIG. 3

FIG. 4

FIG. 5

FIG. 1 is a perspective view of a diaper clasp embodying my new design.

FIG. 2 is a top plan view thereof.

FIG. 3 is a side elevational view thereof, the side opposite being substantially similar therewith.

FIG. 4 is a front end view thereof.

FIG. 5 is a rear end view thereof.

I claim:

The ornamental design for a diaper clasp, substantially as shown and described.
